AUGUSTA PICKERING COOLBROTH, OF CAMBRIDGE, MASSACHUSETTS.

GARTER.

1,156,393.

Specification of Letters Patent.

Patented Oct. 12, 1915.

Application filed June 3, 1914. Serial No. 842,763.

To all whom it may concern:

Be it known that I, AUGUSTA PICKERING COOLBROTH, a citizen of the United States, residing at Cambridge, county of Middlesex, Commonwealth of Massachusetts, have invented certain new and useful Improvements in Garters, of which the following is a specification.

This invention relates to hose supporters and particularly to an inelastic garter. The inelastic garter presents numerous features of desirability over the usual elastic type, of which the freedom from the harmful binding effect and resultant restriction of circulation produced by the elastic webbing is characteristic. The principal difficulty and chief objection to such inelastic garters as have been made, consists in the fact that it has been found practically impossible to get the inelastic webbing to conform to the varying surface contour presented by the limb muscles in their flexing movements. This has been due chiefly to the fact that the webs have been improperly disposed particularly at their points of juncture with each other. Another serious objection to such garters as have been devised lay in the fact that in use the webs tended to turn inward and assume a horizontal position relative to the limb so as to present to the limb a cutting edge which chafed and was exceedingly annoying and uncomfortable to the wearer. To the end therefore of producing an inelastic garter which will be free from these objections and at the same time will be inexpensive, reliable and durable, I have devised my present invention in which I provide for a conformation of the webbing to the varying limb contour as presented in the different flexing movements of the limb, that is to say the downward pull of the hose secures a parallelism at the sides of the garter and effects a flat drawing in of the sides against the limb. This causes the webs to have a strong sustaining effect, due to the lateral or sidewise pressure which they exert and an increased frictional hold owing to the fact that they are held flat and in uniform contact with the limb as distinguished from the uneven strain presented in a round or semi-round garter. In addition the webs are so adjusted relatively as to assume a constantly vertical parallel position relative to the limb so as not to present an edge which will chafe the limb. These and other

features which will appear more fully hereinafter are secured by my present invention, the construction and principle of which will be more fully described in the specification which follows. In the drawings forming a part of that specification I have shown as an illustrative embodiment a form of garter which not only clearly illustrates the principles involved, but is in itself a form proven to be well adapted to the requirements of manufacture and is satisfactory in practice.

In the drawings: Figure 1 is an elevation of a garter in accordance with my invention and Figs. 2, 3, and 4 are transverse sections on the lines 2-2, 3-3, and 4-4 respectively of Fig. 1.

The garter thus illustrated consists of two lateral webs 1 and 2, two back juncture web pieces 3, two front juncture web pieces 4 and a suspension tab 5 carried by the webs 4. All the webs are by preference made of inelastic material which can be produced in ordinary continuous strips and then cut off in the desired lengths.

The lateral webs 1 and 2 are similar and a description of one will suffice. Each web is disposed in the form of a continuous strip and one web is looped through a slot 85 created attaching and guiding member 6 carried by one of the web pieces 4. One end 7 of the lateral strip is looped over the cross bar 8 of an adjustable slide 9 and sewed to the body portion of the strip as indicated 90 in Fig. 3. The other end 10 of the strip is passed over the cross bar 8 of the slide and through the slots defined by said cross bar and the sides of the slide as seen in Fig. 3 and extends as a free engaging end 11 back 95 toward the adjacent rear webbing piece 3.

Each end 11 of the strips 1 and 2 is attached to its webbing piece 3 by turning its free end 11¹ under and sewing to the similarly turned end 3¹ of the piece 3. Each 100 piece 3 therefore backs a strip 11 for a part of its length and is secured at its opposite end to said strip as shown in Fig. 2 by turning its end 11² over and stitching it through the web end 11.

The two web pieces 3 are brought together at an upwardly pointing angle of about ninety degrees so as to present a smooth flat surface to the limb and secure a vertical disposition of the strips 1 and 2 relative to 110 the limb. This insures that the strips 1 and 2 and the webs 3 will lie smooth and flat and

will not form wrinkles or creases which cut or press into the skin. This vertical disposition of the strips causes them to lie parallel to the limb so as not to present a cutting edge to the limb. The web pieces 3—3 are secured to each other in any desired manner, as by stitching or otherwise.

The front web pieces 4 are of two-ply thickness. The guide member 6 is secured 10 to one of the front web pieces 4 by a loop 12 passing through the slot of the guide member and stitched between the inturned ends 13 of the two-ply web 4. The plies near their opposite ends 14 are turned under and 15 spaced slightly apart so as to define with the corresponding opposite web piece 4 an open recess in which is secured the suspension tab 5 which carries the hose engaging devices 15.

20 One of the web pieces 4 has stitched to it a loop end 16 in which is engaged an eye member 17 adapted to engage the coöperating hook member 18 carried by one of the lateral strips 2. The front web pieces 4 are 25 brought together so as to bisect the exterior angle and lie at a downwardly pointing angle of substantially ninety degrees.

The arrangement of the front and back web pieces is such that the downward pull 30 of the hose is distributed over the whole area of the garter instead of being upon the two side strips 1 and 2 which would thus be drawn in tightly against the limb and tend to restrict the circulation.

35 Various modifications in the form and construction of my device may obviously be resorted to within the limits of the appended claims.

What I therefore claim and desire to secure by Letters Patent is:

40 1. A garter of the class described comprising a hose engaging member and a pair of limb encircling members attached to said

hose engaging member at an obtuse angle and meeting each other at substantially a 45 right angle in the rear.

2. A garter of the class described comprising a pair of limb encircling members and united in the rear at an upwardly pointed angle and in the front at a downwardly 50 pointed angle.

3. A garter of the class described comprising a pair of limb encircling members formed of straight webs of material and united in the rear at an upwardly pointed 55 angle and in the front at a downwardly pointed angle.

4. A garter of the class described formed of webs of material and consisting of lateral sections having oppositely disposed points 60 of juncture at angles of substantially 90° or greater and a hose engaging member dependingly attached to said garter at one of said points of juncture, whereby the portions of said lateral sections intermediate of 65 their ends are brought into substantially vertical edgewise position relative to the limb.

5. A garter of the class described formed 70 of webs of nonelastic material and consisting of lateral sections having oppositely disposed front and rear points of juncture, in the form of attached web pieces, and a hose engaging member dependingly attached to the front web pieces whereby the 75 portions of said lateral sections between their ends are brought into substantially vertical edgewise position relative to the limb, and means for adjusting the effective 80 encircling capacity of said lateral sections.

In testimony whereof I affix my signature in presence of two witnesses.

AUGUSTA PICKERING COOLBROTH.
